DOOR LOCK

Edwin W. North and Francis L. Erickson, Rockford, Ill., assignors to National Lock Company, Rockford, Ill., a corporation of Delaware

Application June 18, 1954, Serial No. 437,658

12 Claims. (Cl. 70—146)

The present invention relates to a door lock and more particularly to a novel door lock assembly having an inner and an outer knob for retracting a latch bolt to permit opening of the door, the inner knob being provided with a turn button adapted to lock the outer knob against turning movement and retraction of the latch bolt.

Among the objects of the present invention is the provision of a novel door lock in which the inner knob is provided with a novel turn button assembly for locking the outer knob against turning movement, and a novel cam and tube assembly upon which the outer and inner knobs are mounted in such manner that the inner knob may be rotated and the door opened from the interior when the turn button is in locked or unlocked position, but the outer knob is capable of turning to retract the latch bolt only when the inner knob is unlocked. In the disclosed embodiment, the locking of the outer knob from the interior by turning the turn button of the inner knob maintains the outer knob against turning movement until the turn button is released, thereby preventing access from the exterior to the interior of a room or other enclosure except by means of the requisite key for turning the lock tumbler in the outer knob to unlock the door.

Another important feature of the present invention is the provision in a door lock of a novel cam and tube assembly upon which the outer and inner knobs are mounted and housing the locking mechanism for controlling turning of the outer knob.

A further object of the present invention is the provision in a door lock of a novel cam tube, inner tube and sleeve assembly mounted in concentric relation and so constructed, arranged and connected that when the outer cam tube and its outer knob are locked against rotation, the sleeve carrying the inner knob and the inner tube connected thereto are permitted to rotate relative to the cam tube to thereby retract the latch bolt without turning or releasing the cam tube and its outer knob from locked position.

Another important object of the present invention is the provision in a door lock of a novel means and mechanism for retracting a latch bolt and including a novel cam tube, inner tube and sleeve assembly including a split cam tube upon which the outer knob is mounted and adapted to carry a key-actuated tumbler lock, a split sleeve adapted to carry an inner knob provided with a turn button, and an inner tube carried in the adjacent ends of the cam tube and sleeve all connected into an assembled unit in such manner that the sleeve and inner tube rotate together and the inner tube and cam tube are connected for limited rotation therebetween, whereby the outer knob and its cam tube may be locked against rotation while permitting the inner knob, sleeve and inner tube to rotate and withdraw the latch bolt.

The present invention further comprehends a novel housing assembly for a door lock in which the cam tube is journaled in the opposite end walls of the housing.

2

A further object of the present invention is the provision in a door lock assembly of a novel turn button assembly for locking the exterior or outer knob against turning movement.

5 Further objects are to provide a construction of maximum simplicity, efficiency, economy and ease of assembly and operation, and such further objects, advantages and capabilities as will later more fully appear and are inherently possessed thereby.

10 In the drawings:

Figure 1 is a perspective view of the novel lock construction as it appears when completely assembled for use in a door or other closure.

Fig. 2 is a disassembled view of the separate latch bolt unit disconnected from the cam and tube assembly with its assembled housing, outer clamp plate, outer escutcheon and outer knob, and showing these two assemblies ready to be inserted into their respective bores in a door or other closure, after which the inner clamp plate, inner escutcheon and inner knob are assembled upon the cam and tube assembly to complete the assemblage.

Fig. 3 is an enlarged view in horizontal cross section taken longitudinally through the assembled lock construction, except for the latch bolt assembly which is shown in plan, and illustrating the manner of mounting it in a door or other closure.

Fig. 4 is a view in front elevation of the housing assembly and its disassembled outer and inner clamping plates.

20 Fig. 5 is a view in vertical cross section taken on the line 5—5 of Fig. 3 and viewed in the direction of the arrows.

25 Fig. 6 is a fragmentary enlarged view in vertical cross section taken longitudinally through the outer knob and assembled lock cylinder with the key inserted to release the latch bolt when the outer knob is locked from the interior of the door.

30 Fig. 7 is a top plan view of the cam and tube assembly, together with the housing.

35 Fig. 8 is an exploded or disassembled view in perspective of the component parts of the cam and tube assembly of Fig. 7, but showing the parts on a smaller scale than in Fig. 7.

40 Fig. 9 is a view similar to Fig. 3 but showing the lock assembly without the key lock and with a modified form of housing assembly.

45 Fig. 10 is a view in front elevation of the housing assembly and its disassembled outer and inner clamping plates shown in Fig. 9.

50 Referring to the disclosure in the drawings and more particularly to the novel illustrative embodiment there-in shown, the disclosed embodiment of a lock assembly is adapted for use with a door or closure having an outer knob adapted to be locked or unlocked from the interior of a room or other enclosure by the rotation of a turn button. When the turn button on the inner knob is manually turned or moved to unlocked position, the door may be freely opened from the interior as well as from the exterior by a mere turning of either knob which in turn retracts the latch bolt.

55 Upon manual turning of the button to locking position the outer knob is locked against turning movement but the inner knob may be turned to retract the latch bolt and permit opening of the door from the interior. However, such turning of the inner knob without turning of the turn button does not release the outer knob for turning and does not release the turn button from its locked position so that upon again closing the door the door is locked to the exterior. In the embodiment shown in Figs. 1 to 7, inclusive, the door may be unlocked from the exterior by a key inserted into the cylinder of a tumbler

or lock mounted within the outer knob, so that upon turning of the key the latch bolt is retracted.

In the embodiment shown in Figs. 1 to 7, inclusive, the novel lock construction includes an outer knob 10 mounted at the exterior of a door or closure 11 upon the outer end of a split cam tube 12, and an inner knob 13 mounted at the interior of a door or closure upon a split sleeve 14. These knobs 10 and 13 are securely but detachably mounted on the opposite ends of a cam and tube assembly shown in greater detail in Figs. 7 and 8, and which includes the split cam 12, an inner tube 15 and the sleeve 14 all connected together in such manner that the inner tube 15 and its external sleeve 14 which encompasses and conformably receives the inner end of the inner tube 15 are securely or fixedly connected together, but the split cam tube 12 which encompasses and conformably receives the outer end of the inner tube 15 is capable of turning upon the outer end of the inner tube through a limited arc of travel, but affixed thereto against longitudinal movement.

To connect the cam tube 12 to the inner tube 15 for limited rotation therebetween, the cam tube is provided at 16 with two narrow transverse slots adjacent the inner end of this cam tube whereby to provide a relatively narrow connecting strip 17 adapted to be depressed or indented into an arcuate slot 18 in an intermediate portion of the inner tube 15, thereby staking the parts together but permitting limited rotation therebetween.

The cam tube 12 is longitudinally split or slotted at 19 with this slot extending for a substantial portion of the length of the tube and adapted to receive a detent 21 on the knob 10 fitting conformably within the slot 19 and thereby aligning the knob 10 upon the cam tube 12 and permitting its ready assembly by sliding the knob longitudinally onto the cam tube (Fig. 3). To detachably connect the outer knob 10 in anchored position, the cam tube 12 at a point diametrically opposite the longitudinal slot 19 is provided with a recess or opening 22 adapted to receive a button 23 (Figs. 3, 7 and 8) staked or affixed to an arcuate expansible or snap spring 24 carried within and upon the inner cylindrical wall of the cam tube and forcing this button 23 outwardly through the recess or opening 22. To receive the projecting end of this button, the neck of the outer knob 10 is provided with a recess or opening 25 which when aligned with the button 23, the latter snaps into locking engagement in the recess and retains the outer knob 10 assembled on the cam tube 12. The cam tube is further provided with diametrically opposed longitudinally extending slots 26 open at their outer end for slidably receiving a key lock assembly 27 in the outer knob 10 (Figs. 3 and 6).

The inner knob 13 is adapted to be mounted upon and detachably anchored to the split sleeve member 14 by means of a detent 28 adapted to be conformably received in a longitudinally extending slot 29 in the sleeve member (Figs. 1, 2 and 3) and a spring-pressed knob holder 31, the projecting end of which extends through a transverse slot 32 in the sleeve 14. A leaf spring 33 has one end 34 anchored in a slot in the holder and the other end 35 bent and received and anchored in a transverse slot 36 spaced from the transverse slot 32, whereby the projecting end of the knob holder 31 is spring-biased to elevated or extended position. This leaf spring 33 is located in a longitudinally extending slot 37 and flattened end portion 38 of the inner end of the inner tube 15 (Figs. 7 and 8). The projecting end of the knob holder 31 is adapted to be received in an elongated, transverse slot 39 in the neck of the knob whereby the inner knob 13 is detachably locked to the sleeve 14.

The sleeve 14 is attached or rigidly anchored to the inner concentric tube 15 by means of a pair of oppositely disposed tongues 41 (Figs. 2, 7 and 8), each of which is bent or staked into an aligned longitudinally extending slot 42 at the opposite end of a circumferentially extending groove 43 in the inner tube 15.

The outer end of the inner tube 15 is provided with

spaced, inturned flanges 44 (Figs. 3, 6 and 8) conformably receiving the projecting end 45 of the key lock assembly 27, and the tube receives therein in sequence a guide ring 46 disposed adjacent the flanges 44, a guide coil spring 47, a guide washer 48 having a peripheral portion thereof cut away at 49, and a locking lever or slide bar 50. This locking lever or slide bar is provided at its outer end with a laterally projecting leg 51 having spaced projections 52 and 53, the projection 52 extending into and centered in an opening 54 in the guide washer 48 and the leg 51 being adapted to be moved into locking engagement with a slot in an end plate or end wall 55 of a stationary housing 56 (Figs. 2, 4, 5 and 6).

Adjacent the laterally projecting leg 51, the locking lever or slide bar 50 is notched at 57 (Fig. 8) and its inner end 58 reduced and projecting into a turn button assembly 59. This latter assembly includes a bushing 61 having a transverse plate 62, diametrically spaced, longitudinally extending arms connecting the plate 62 to a pair of arcuate portions 63 fitting conformably within the hollow interior of a turn button 64 (Fig. 3). Also mounted within the turn button is a washer having an annular peripheral flange 65 conformably fitting within the turn button and a cupped or annular reduction 66, with the bushing 61 and washer secured or staked within the turn button 64 by spaced indents 67 to complete the turn button assembly (Fig. 8).

The guide spring 47 spring-biases the locking lever or slide bar 50 toward the inner knob end of the assembly (Fig. 3) and tends to move this locking slide bar 50 out of its locking position in the end plate or wall 55 of the stationary housing 56. In assembled position, the elongated reduced end 58 of the locking lever or slide bar 50 projects through an opening 68 in the transverse plate 62, through an aligned opening in the cupped or annular reduction 66 of the washer and into the hollow of the turn button 64.

The transverse plate 62 carried by the turn button 64 has opposed projections 69 one of which is provided with a tongue 71 (Fig. 3) projecting into a camming slot 72 having a lip 73 adjacent its narrow end 74 providing a recess for the reception and retention of the tongue 71 when the turn button 64 is rotated and forced inwardly to move the locking lever or slide bar 50 to locking position, and its other or wide end 75 provided with a recess to receive the tongue 71 when the turn button is moved through an arc of approximately 90° to unlocked position. The inner knob 13 is provided with a central opening having an inturned flange 76 defining this opening and providing a bearing for rotating and sliding movement of the turn button 64. The outer knob 10 is provided with a similar opening defined by an inturned, cylindrical flange 76 for rotatably mounting the plug 77 of the key lock assembly 27.

The split cam 12 is cut away or notched (Fig. 8) adjacent its inner end at 78 to provide longitudinally extending and spaced camming edges 79 and cut away or notched at 80. The inner tube 15 is also longitudinally notched or cut away at 81 adapted to be aligned with the notch 78 when the split cam 12 and the inner tube 15 are assembled and secured in assembled relation, and provided with longitudinally extending and spaced camming edges 82.

The cam and tube assembly is journaled or rotatably mounted in the stationary housing 56 (Figs. 1, 2, 3, 4, 5 and 7) comprising a substantially cylindrical wall 83 cut away or notched to provide an opening 84 defined by a pair of inturned and opposed flanges 85 each provided at its outer end with a projecting lip 86. The cylindrical wall 83 is further provided with spaced and substantially diametrically opposed inturned tongues or flanges 87 (Figs. 5 and 7) stamped and bent or formed inwardly with either providing a fulcrum about which a floating push plate or follower 88 is adapted to pivot or rock. This push plate or follower 88 seats or bears against

the end of a pusher or slide member 89 for retracting the latch bolt 91.

The push plate or follower 88 is of substantially greater width at its end 92 and thereat provided with inturned flanges 93. At its other or narrower end it is also provided with similar flanges 94 each bent inwardly to form enclosures as will be clearly apparent from Fig. 5, with the enclosures formed by the flanges 93 adapted to receive the ends 95 of a coil spring 96 suitably anchored in the housing 56. The ends 95 of the coil spring 96 spring-bias the push plate or follower 88 to its neutral position as shown in Fig. 5, with rocking of this floating push plate or follower being effected about either in-turned tongue or flange 87, providing a fulcrum on the interior of the housing 56.

The camming edges 79 of the split cam 12 and the camming edges 82 of the inner tube 15 are adapted to engage the flanged, inner side of push plate or follower plate 88 and rock or rotate the latter which rocking movement depresses the pusher or slide member 89 and retracts the latch bolt 91.

When the turn button is unlocked with the tongue 71 in the recess in the widened end 75 of the camming slot 72, either the inside knob 13 or the outside knob 10 may be freely turned. When the unlocked inside knob is turned in either direction, the split sleeve 14 and the connected inner tube 15 are turned and the rotating camming edges 82 on the inner tube engage and rotate the push plate or follower 88 to depress the slide member or pusher 89 and retract the latch bolt 91. When the turn button 64 is in unlocked position, the outer knob 10 is also unlocked and may be turned in either direction to rotate the connected cam tube 12 and cause either camming edge 79 of the camming tube to engage the push plate or follower plate 88 and depress the pusher or slide member 89 for retracting the latch bolt 91.

When the turn button 64 is moved to locked position in which the locking lever or slide bar 50 is moved to the left or outwardly as shown in Fig. 3, the projection 53 on the leg 51 of this locking lever or slide bar seating within a slot 97 in the end wall 55 of the stationary housing 56 and the laterally projecting leg 51 enters the inner end of the slot 19 in the cam tube 12 so as to lock the cam tube 12 and the outer knob 10 against rotation. However, in such locked position of the turn button 64 the inner knob may be freely rotated to open the door 11 from the interior, the knob in turn rotating the inner tube 15 and rocking the follower plate or push plate 88 to depress the slide member 89 and retract the latch bolt 91. But such turning movement of the inner knob 13 does not release the locking lever or slide bar 50 from its locked position in the fixed end plate 55 on the stationary housing 56 so that the outer knob 10 and its cam tube 12 cannot be rotated. In order to then release the latch bolt 91 from the exterior of the door 11 it is necessary to insert the proper key 98 in the plug 77 of the key lock assembly 27 whereby turning of the key will rotate the inner tube 15 and rock the follower plate or push plate 88 to retract the latch bolt 91.

The key lock assembly 27 includes the plug 77 fitting conformably in the opening defined by the inturned flange 76 in the outer knob 10, and carrying plural tumblers 101 in radial recesses, a cylinder 102 carrying aligned drivers 103 for the tumblers and each driver spring-pressed by a coil spring 104 seating at its upper or outer end against a retainer 105. A plug ring 106 carrying the lug or projecting end 45 extends into the inner tube 15 and thereat engages the inturned flanges 44 on the outer end of the inner tube 15 whereby when the proper key 98 is inserted into the key lock assembly the key may be rotated and it in turn rotates the plug 77 and the plug ring 106 whereby the inner tube 15 is rotated to cause one of its camming edges 82 to rock the follower plate or push plate 88 and retract the latch bolt 91.

Rotation of the inner tube 15 with the locking lever or slide bar 50 in its extended, locked position in the inner end of the slot 19 in the cam tube 12 adjacent the notched portion 80 is permitted by reason of the slot 81 in the inner tube 15 and the connection between the cam tube 12 and inner tube 15, whereby the inner tube may rotate through an arc sufficient to allow its camming edges 82 to abut and rock the follower or push plate 88 to depress the slide member or pusher 89 and retract the latch bolt 91. At the same time the cam tube 12 is prevented from being rotated by the location of the leg 51 of the locking lever or slide bar 50 in the slot 19 and also in the slot 97 in the end wall 55 of the stationary housing 56.

The end wall or plate 55 of the housing 56 is provided with a hub 107 providing a bearing for rotatably receiving the cam tube 12, and is externally threaded for detachably receiving the internally threaded hub of a clamping plate 108. This clamping plate 108 is adapted to be adjusted and bear against the exterior of the door 11 as shown in Fig. 3, and is enclosed by an escutcheon 109 which covers this external clamping plate and is preferably affixed thereto by indentations 111 on its peripheral flange 112 interlocking with grooved portions on the peripheral edge 113 of the clamping plate 108.

The end wall 55 is rigidly fixed or secured to the outer edge of the cylindrical portion 83 of the stationary housing 56 by providing this outer edge with crimped or undulated flanges or tongues 114 projecting outwardly from the cylindrical wall 83 of the housing 56 over the end wall 55. An inner end wall or plate 115 is secured to the opposite end of the stationary housing 56 by crimped or undulated flanges or tongues 116 projecting from the cylindrical wall 83 and crimped over the end wall 115 of the housing 56. This end wall 115 is provided with an outwardly projecting hub 117 providing a bearing for the cam tube 12, and is provided with a pair of spaced projecting machine screws 118 adapted to receive a removable inner clamping plate 119. These screws are adapted to project through aligned keyhole slots in the inner clamping plate whereby when this inner clamping plate 119 is mounted over the head of the screws 118 and is rotated so that the heads of these screws are disposed in the narrow ends of the keyhole slots and the screws tightened, the inner clamping plate bears against the inside of the door 11 and the lock assembly is held in fixed position.

An escutcheon 121 is mounted over the inner clamping plate 119 and detachably held in assembled relation by spaced snaps or detents 111 detachably interlocking with the peripheral flange or edge 122 of the inner clamping plate 119. After the escutcheon has been assembled, the inner knob 13 is then assembled and locked in position by the knob holder 31.

For locating the end plates or walls 55 and 115 of the housing 56 in their proper location and spaced relation, the cam tube 12 is shown in Figs. 3, 5 and 8 as provided with a pair of projections 123 providing spaced stops or abutments.

When the cam tube 12, inner tube 15, sleeve 14 and the component parts of the locking mechanism shown in Fig. 8 are assembled, the inner tube 15 is inserted into the cam tube 12 with the outer end of the inner tube containing the inturned flanges 44 being positioned adjacent the annular spring 24 (Fig. 7) and the strip 17 adjacent the inner end of the cam tube 12 is indented into the arcuate, transverse slot 18 of the inner tube 15 whereby to lock these concentric members together with the slot 18 being of sufficient length to permit limited rotation therebetween whereby the camming edges 82 of the inner tube 15 actuate the follower or push plate 88 to retract the latch bolt 91 upon turning of the inner knob 13 and its sleeve 14. Then the guide ring 46, the guide coil spring 47, the guide washer 48 and the locking lever or sliding locking bar 50 are inserted into the inner sleeve 15, with the projection 52 of the locking bar 50 received

in the opening 54 of the guide washer 48 and the ends of the cut-away peripheral portion 49 of this guide washer seating upon the camming edges 82 of the inner tube 15 and rotatable therewith. The split sleeve 14 is secured to the inner end of the inner tube 15 by depressing the tongues 41 into the longitudinal slots 42 at the ends of the circumferential groove 43 of the inner sleeve, the knob holder 31 and spring 33 are assembled in operative position and the turn button assembly 59 is mounted in the inner end of the split sleeve 14 with the tongue 71 on the transverse plate 62 of the turn button assembly projecting into the camming slot 72.

The housing 56 with its end plates 55 and 115 is assembled on the cam tube and sleeve assembly in the manner shown in Fig. 7. Next the outer clamping plate 108, escutcheon 109, key lock assembly 27 and outer knob 10 are assembled to form the unit assembly shown in Fig. 2 for insertion through a transverse bore 124 in the door 11.

The latch bolt assembly or unit designated generally by the reference numeral 125 and also shown disassembled in Fig. 2, includes the slide or pusher 89, the latch bolt 91 and its actuating mechanism in the latch bolt housing 126 and its face plate 127 fixed to the housing, is adapted to be inserted in a bore in the edge of the door 11 and secured to the door in the manner shown in Fig. 3.

In the assembly of these pre-assembled units, the housing 56 and its assembly is inserted into the transverse bore 124 in the door 11 to a position in which the pusher or slide member 89 on the inner end of the latch bolt unit or assembly 125 may enter the opening 84 in the housing 56, and when the oppositely opening channels 128 on the inner end of the latch bolt housing 126 are aligned with the flanges 85 on the housing 56, moving the housing assembly until the outer clamping plate 108 abuts the door 11 causing the oppositely projecting tongues or lips 86 on the housing 56 to enter the channels 128 and the pre-assembled units are held in their proper assembled relation as shown in Fig. 1. The face plate 127 is then secured to the edge of the door 11 by screws or other attaching means and the inner clamping plate 119, its escutcheon 121 and the inner knob 13 are applied in sequence and assembled in their proper operative relation.

Figs. 9 and 10 disclose an alternate embodiment of the present invention in which the outer knob 129 is not provided with an opening to receive a key lock assembly and this knob is staked at 131 to the cam tube 12. In this embodiment, the housing 132 comprises a cylindrical part 133 and an end wall or plate 134 secured thereto by spaced longitudinally extending flanges 135 and 136 projecting through aligned slots in the end plate, with the projecting ends of flanges 135 and 136 deformed to lock the end wall to the housing. This end wall is provided with a hub 137 encompassing the cam tube 12 and held in alignment by means of projections 138 upstanding from the cam tube.

The inner end of the cylindrical part 133 of the housing 132 is provided with oppositely disposed inturned flanges 139, each tapped to receive a machine screw 141 for receiving a clamp plate 142 provided with a recess or slot 140 to permit the plate to slip over the knob holder 31. This inner clamp plate is provided with oppositely disposed bayonet slots each adapted to receive the head of a screw 141, and when rotated to dispose the shank of the screw in the narrow end of the bayonet slot with the locating lugs 140 located in the transverse opening 12 in the door 11 and the screws tightened, attaches the clamp plate 142 upon the housing and locks it against the adjacent face of the door. Like the end wall or clamp plate 134, this clamp plate 142 is provided with a hub 143 in which the inner end of the cam tube 12 is journaled.

Unlike the embodiments shown in Figs. 1 to 8, in-

clusive, the outer end wall or plate 134 bears against the outer face of the door 11 and is adapted to receive an escutcheon 144. Any adjustment relative to the thickness of the door is accomplished by adjusting the inner clamp plate 142 which functions as a combined end wall and clamping plate for the housing and on which the inner escutcheon 144 is mounted.

In other respects the component parts of this alternate assembly are similar to that of the embodiment of Figs. 1 to 8, inclusive, and like reference characters have been applied to similar parts.

In this latter form of the invention, the housing assembly is of simplified construction and of decreased cost, and although it does not permit the range of adjustment contemplated by the housing embodied in the lock of Figs. 1 to 8, inclusive, it has the advantage that in prefabricated homes and in ready-hung doors, the latch bolt assembly may be initially mounted in the door for shipment and at the place of final installation the housing and its cam tube assembly may be readily inserted to complete the lock assembly.

Having thus disclosed the invention, we claim:

1. In a door lock construction including a latch bolt, a stationary housing including a substantially cylindrical part and end walls adapted to be received and fit conformably in a transverse bore in the door, a split cam tube journaled in the end walls of the housing, a knob secured to the outer end of the cam tube, a split sleeve, a knob secured to the inner end of the sleeve, an inner tube arranged in concentric relation within the adjacent end of the cam tube and sleeve, means for connecting the inner end of the inner tube to the sleeve whereby the sleeve and inner tube rotate together, means for connecting the inner tube to the cam tube but permitting the inner tube limited rotation within the cam tube, said cam tube and said inner tube each being slotted to provide thereon longitudinally extending, spaced camming edges, the camming edges on the cam tube being rotated by turning of the outer knob and the camming edges of the inner tube being rotated by turning of the inner knob, an opening in the cylindrical part of the housing aligned with the slots in the cam tube and inner tube, and a floating push plate in said opening in the housing and adapted to retract the latch bolt when rocked by turning of the outer knob and its cam tube or by turning of the inner knob, its sleeve and the inner tube.

2. In a door lock as set forth in claim 1, including a turn button carried by the inner knob and projecting into the split sleeve and through the inner knob, and locking means in the inner sleeve actuated by turning of the button for locking the cam tube to the stationary housing when the turn button is turned in one direction to prevent the cam tube and its outer knob from turning to retract the latch bolt.

3. In a door lock as set forth in claim 1, including a turn button carried by the inner knob and projecting through the inner knob, and a locking bar slidably mounted in the inner tube and actuated by turning of the turn button in one direction to lock the cam tube and its outer knob against rotation until the turn button is turned to release position.

4. In a door lock as set forth in claim 1, including a turn button carried in the inner knob and projecting into the split sleeve, a lateral projection on and rotatable with the turn button, a cam slot in the split sleeve with an end of the lateral projection extending into the cam slot for controlling longitudinal movement of the lateral projection and the turn button, and spring-biased locking means carried in the inner tube and movable longitudinally therein upon turning movement of the turn button, said locking means engageable in the split of the cam tube and locking this cam tube and its connected outer knob against rotation when the turn button is turned in one direction and releasing the cam tube and outer knob when the turn button is turned in the other direc-

tion, whereupon the spring-biased locking means is moved to inoperative position.

5. In a lock construction for a door or other closure having a retractable latch bolt, an assembly including a cam tube having its outer end extending to the exterior of the closure, a knob mounted on the outer end of the cam tube and adapted to rotate the latter to retract the latch bolt, a sleeve at the interior of the closure, a knob mounted on the sleeve for rotating the sleeve from the interior of the closure, an inner tube connecting the cam tube and sleeve with the inner tube rigidly connected to the sleeve for rotation therewith but connected to the cam tube in such manner as to permit limited rotation between the cam tube and the inner tube, a housing having end walls each provided with a bearing in which the cam tube is rotatably mounted, said cam tube and inner sleeve provided with spaced camming edges and said housing having an opening aligned with said camming edges, a spring-biased follower plate loosely mounted in the opening in the housing for retracting the latch bolt when the cam tube is rotated by the outer knob and either of its camming edges rocks the follower plate to retract the latch bolt, or the inner tube and sleeve are rotated by the inner knob whereupon either cam edge of the inner tube rocks the follower plate to retract the latch bolt, a turn button carried in the inner knob and a locking bar actuated by turning of the turn button in one direction to engage and lock the cam tube and its outer knob against rotation and releasing the locking bar from engagement with the cam tube when the turn button is turned in the other direction.

6. In a lock construction as set forth in claim 5, including a key lock mounted in the outer knob and cam tube and having a projection engaging the outer end of the inner tube for rotating the inner tube to rock the follower plate and retract the latch bolt while the cam tube and outer knob are locked against rotation.

7. In a lock construction as set forth in claim 5, including a key-operated tumbler lock carried in the outer knob, and adapted to rotate the inner tube to rock the follower plate and retract the latch bolt without unlocking the cam tube and its knob.

8. In a door lock assembly for retracting a latch bolt to permit opening of the door, a housing having an end plate at the opposite ends of the housing, a cam tube extending through the housing and journalled in the end plates, an inner concentric tube in the cam tube, means for connecting the outer end of the inner tube to the cam tube but permitting limited rotation therebetween, a sleeve encompassing the inner end of the inner tube and affixed thereto, an outer knob mounted on and affixed to the outer end of the cam tube for rotating the latter, an inner knob mounted on and affixed to the sleeve for rotating the sleeve and the inner tube relative to the cam tube and its knob, a turn button carried in the inner knob and having a projection rotatable and movable longitudinally of the sleeve in a camming slot provided in the sleeve, and a locking bar actuated by said push button and slidably mounted in the inner tube for locking the cam tube and the outer knob against rotation.

9. In a lock construction for a door or other closure having a retractable latch bolt, a stationary housing fitting conformably in a transverse opening in the closure, a split cam tube projecting through and rotatably mounted in the housing, a knob mounted on the outer end of the cam tube to rotate the latter, a split sleeve adjoining the

inner end of the cam tube, a knob for the interior of the closure mounted on and rotating the sleeve, an inner tube conformably received in the adjoining ends of the sleeve and cam tube, means for connecting the inner tube and sleeve whereby they rotate together upon turning the inner knob, means for connecting the inner tube to the cam tube whereby the inner tube is rotatable relative to the cam tube, said inner tube and cam tube each being slotted to provide spaced camming edges and said housing provided with an opening aligned with the slots of the cam tube and inner tube, a floating push plate mounted in the opening in the housing and adjacent the camming edges of the cam tube and inner tube, means in the housing providing a fulcrum for rocking movement of said push plate in either direction as the cam tube is rotated by its knob, or the inner tube is rotated by turning of the inner knob, locking means carried in the inner tube and a turn button carried by the inner knob, said locking means upon turning of the button in one direction locking the cam tube and its outer knob against rotation but permitting the inner knob, the sleeve and the inner tube to be rotated to retract the latch bolt, and when the button is turned in the other direction releasing the cam tube and permitting either the outer or the inner knob to be turned to release the latch bolt and opening of the closure.

10. In a lock construction as set forth in claim 9, including a key-operated lock carried in the outer knob and cam tube and having means engaging and turning the inner tube to rock the push plate and retract the latch bolt when the cam tube and the outer knob are locked against rotation.

11. In a door lock assembly for retracting a latch bolt to permit opening of the door, a housing having an end plate at the opposite ends of the housing, a cam tube extending through the housing and journalled in the end plates, an inner concentric tube in the cam tube, means for connecting the outer end of the inner tube to the cam tube but permitting limited rotation therebetween, a sleeve encompassing the inner end of the inner tube and affixed thereto, an outer knob mounted on and affixed to the outer end of the cam tube for rotating the latter, an inner knob mounted on and affixed to the sleeve for rotating the sleeve and the inner tube relative to the cam tube and its knob, a turn button carried in the inner knob and having a projection rotatable and movable longitudinally of the sleeve in a camming slot provided in the sleeve, and a locking bar actuated by said push button and slidably mounted in the inner tube, said locking bar having an end projecting into and engaged by the turn button and a projection at the other end received in a slot in the cam tube and another projection at the other end adapted to be received in a slot in the housing for locking the cam tube and the outer knob against rotation.

12. In a door lock assembly as set forth in claim 11, including a key-operated tumbler lock carried in the outer knob and adapted to rotate the inner tube to retract the latch bolt without unlocking the cam tube and the outer knob.
